UNITED STATES PATENT OFFICE.

JOHN ROACH, OF SAN FRANCISCO, CALIFORNIA.

PLUMMET-LAMP.

SPECIFICATION forming part of Letters Patent No. 287,580, dated October 20, 1883.

Application filed July 28, 1883. (No model.)

To all whom it may concern:

Be it known that I, JOHN ROACH, a citizen of the United States of America, residing at San Francisco, in the county of San Francisco and State of California, have invented certain new and useful Improvements in Plumb-Bobs; and I do hereby declare the following to be a full, clear, and exact description of the invention, such as will enable others skilled in the art to which it appertains to make and use the same.

My invention has relation to improvements in plumb-bobs, and is especially directed to provide an instrument of the kind named to be used in places and under circumstances excluding the sun's light; hence the object of the invention is to construct an illuminated plumb-bob, by which the line of perpendicularity may be ascertained or shown by the direction of the flame of a lamp properly protected and controlled.

In the accompanying drawings, forming a part of this specification, Figure 1 is a perspective view of my improved illuminated plumb-bob. Fig. 2 is a view in perspective, showing the several parts detached and relatively arranged. Fig. 3 is a central vertical sectional view, and Fig. 4 is a view showing the instrument suspended from a tripod.

The letter A represents the plumb-bob, made of metal, and of any of the usual configurations. This plumb-bob is formed with a chamber, a, for containing oil or burning-fluid, and is also formed with the rim or flange b, with screw-threads on the outside and inside thereof, for the purposes about to be stated. To the inner screw-threads of the flanges b is fitted the cap B, for closing the oil-chamber. This cap consists of the plate c and screw-threaded annulus d, of less diameter than the diameter of the plate, in order that a shoulder may be formed to rest on the rim of the flange b of the plumb-bob when the cap is screwed home in the plumb-bob. This cap B is also formed or provided with the wick-holder e, which is accurately arranged and adjusted in relation to the vertical centrality of the plumb-bob, that the line of perpendicularity shall be common with the point of the bob and center of the wick-tube.

Attached to the exterior screw-threads on

the flange b is a lantern-frame, or chimney, or holder, C, consisting of the screw-threaded rings f f', connected by the uprights g. The lower ring, f, screws over the ring of the plumb-bob, and is provided with perforations h, serving as air-vents to promote combustion of the lamp, and in the lower ring are fixed inner studs, i, or similar means to serve as supports for the glass chimney. The upper ring, f', of the lantern-frame is perforated substantially as shown at k, for purposes of ventilation, and fitted with a screw-threaded cap or hood, E, to prevent falling water from reaching the flame.

The letter D represents the glass or chimney of the lamp. This may be of any suitable transparent material, such as glass or mica. It finds a seat on the studs i in a lower ring of the lantern-frame, and extends up into the upper ring, but not so far as to prevent the cap of the lantern from being properly adjusted in place. The center of this cap is perforated to receive the cord or wire from which the instrument is suspended. This perforation, the center of the wick-tube, and the point of the plumb-bob are on the same vertical line, in order that the point of suspension, the point of the flame, and the point of the plumb-bob shall register in practice.

The instrument can be suspended, as described, from a tripod or other implement by means of a wire or other material.

It will be readily seen that my invention is peculiarly adapted for use in mining operations, and in like places wherein the sun's light cannot be admitted.

By means of the lantern-frame, with glass or chimneys, I obviate disturbance of the flame or current of air, obtaining a steady, clear flame, the point of which coincides with the point of suspension and point of the plumb-bob.

It is obvious that the cap of the lantern may be made integral therewith.

I reserve the right to vary the construction and arrangement of the parts without departing from the spirit of the invention, and also to use any of the well-known lights now known.

What I claim as my invention, and desire to secure by Letters Patent, is—

1. The plumb-bob herein described, consisting, essentially, of the bob A, cap B, lan-

tern-frame C, and cap or hood E, arranged and combined as set forth.

2. As an improved article of manufacture, the plumb-bob consisting, essentially, of the bob A, having chamber *a* and screw-threaded annulus *b*, the cap B, with central wick-holder, the lantern-frame C, the transparent chimney D, and cap or hood E, the whole arranged and

combined substantially as and for the purposes set forth.

In testimony whereof I affix my signature in presence of two witnesses.

JOHN ROACH.
